UNITED STATES PATENT OFFICE

1,931,172

STOKER

Harry M. Swindler, Dayton, Ohio, assignor to The James Leffel & Company, Springfield, Ohio, a corporation of Ohio

Application February 1, 1930. Serial No. 425,207

34 Claims. (Cl. 110—47)

My invention relates to stokers and in particular to stokers for Scotch marine boilers.

It is my object to provide a stoker which can be utilized in the limited area and peculiar construction of a Scotch marine boiler wherein the fire box is completely surrounded by water of the boiler.

It is my object to provide a stoker that will fit within the limited fire box of such a boiler, will provide means for accumulating and storing the ash, and will provide means for adequately cooling the entire structure, preferably from a single source.

It is a further object of my invention to provide a system of air chambers for balancing the air or apportioning it to the respective sides of the fire box according to the demands for air therein.

It is a further object to utilize the air for cooling the rivet heads, for cooling the fire doors and for creating a suitable draft over the fire bed and through the top of the fire box in order to cause adequate and uniform burning of the fuel throughout the length of the retort.

It is a further object to provide an arrangement of tuyères such as a clinker pocket is formed at each side of the grate away from the coal feeding retort which allows ash and cinders to accumulate without fouling of the air ports with fused ash.

It is a further object to provide positive air circulation under the distributing plate, to provide air cooling and to scavenge coal siftings to allow free and unobstructed movement of the plate as well as air cooling the rivet projections by air flowing under the distributing plates.

It is a further object to provide such air flow, which has then been thus preheated to assist in the combustion of volatile gases distilled at the front part of the furnace.

It is a further object to provide a bridge wall built in as a part of the stoker with removable brick held in place by a common assembly means.

It is a further object to provide means of aligning the tuyères, spacing them from the retort, positioning the retort and forming an air delivery chamber and an air return chamber for cooling the rivet heads, all by a single, radial, detachable means within the fire box.

It is a further object to provide streamline passageways in the tuyères so arranged as to be self-cleaning to prevent the choking of the passageways by fuel whether in lump or in powdered condition.

It is a further object to provide sealed joints to

prevent the sifting of coal dust and the choking of the passages.

Referring to the drawings:

Figure 1 is a vertical section through the outer end of the boiler and stoker mechanism;

Figure 2 is a section on the line 2—2 of Figure 1;

Figure 3 is a similar view to Figure 1 showing the remainder of the boiler and stoker in section;

Figure 4 is a section on the line 4—4 of Figure 1;

Figure 5 is a section on the line 5—5 of Figure 1;

Figure 6 is a section on the line 6—6 of Figure 1;

Figure 7 is a section on the line 7—7 of Figure 3;

Figure 8 is a section on the line 8—8 of Figure 3;

Figure 9 is a section of the line 9—9 of Figure 3;

Figure 10 is a detail view of the air control and damper mechanism;

Figure 11 is a section on the line 11—11 of Figures 1 and 3.

Referring to the drawings in detail, 1 indicates the outside shell of the boiler having the tubes 2 and the cylindrical fire box 3, which is completely surrounded by water indicated at 4.

The limited area of this fire box has heretofore been regarded as making it impossible to provide an automatic, continuous operation of a stoker, which would be self-cleaning of ash and clinker, that could be readily accessible and which could be removable as a unit or in sections.

The cylindrical fire box 3 is attached to the outside boiler wall 1 by a plurality of rivets 5. The heads of these rivets at the entrance to the fire box project inwardly as at 6 into the fire box area.

Within the fire box is mounted a retort for receiving the coal, such retort being comprised of side walls 7 and 8 and a sloping rear end wall 9. The side walls 7 and 8 are extended beyond the rear wall 9 and are joined together by a vertical wall 45 hereinafter described. The legs 10 provide a support for the retort upon the bottom of the fire box and rest on the fire box between the rivet heads 6.

The bottom of the retort has a shoulder on either side thereof as at 11 for receiving the edges of the reciprocating pusher plate 12. This pusher plate is provided with pusher shoulders 13 that are detachably mounted thereon by the bolts 14. The forward end of the pusher plate 12 slidably rests upon a horizontal portion 15 that forms an under bottom of the retort and is a continuation of the rear wall 9. Suitable ribs 16 are provided on the bottom of the pusher plate 12 for its adequate reinforcement.

The upper edges of the retort are provided with a laterally extending flange 17 which serves as

the inner support for the tuyères 18. The tuyères comprise a body having an inner jaw 19, one face of which 20 rests upon the flange 17 and the other portion of which 21 extends beneath the flange.

5 The retort face of the tuyères is provided with a plurality of inwardly extending and upwardly directed openings 22, the inner ends of which at 23 are directed downwardly and are separated by streamline partitions 24. These partitions are 10 directed from the retort end at an angle to the inward movement of the coal along the retort so that the inner ends of the passageway are closer to the doors of the fire box than the retort ends of the passageways, thus making the tuyères self 15 cleaning.

The cap of the tuyère is formed with an arcuate inner end 25 which proceeds from the inner surface adjacent the fuel retort upwardly and then downwardly towards the wall of the fire box 20 forming an arcuate bed 26 for receiving the ash and clinker, which is rolled over and pushed to the outer wall of the fire box out of the way as the fuel is moved from the retort by the pusher and is consumed. The outer ends of these tuyères 25 are arcuate at 27 to fit the inside of the fire box and are provided with depending ribs 28 which rest upon the horizontal plate 29 of the arcuate spacer 30. This spacer is provided with a vertical flange 31 which engages the vertical face 30 of the side walls 7 and 8 of the retort respectively.

The shoulders 32 of arcuate shape are located within this arcuate spacer 30, the shoulders 32 being formed on the wall 45 and having cut away 35 portions in one of them as at 32a for clearing the higher rivet 32b at the overlapping of the fire box wall 3. The space thus formed as at 33 and 34 is utilized for the air supply through the openings 22 in the tuyères for the combustion of the fuel. As will be hereinafter described, the 40 return air returns from the spaces 33 and 34 through 36a to the space 37, whence the air proceeds forwardly underneath the retort to the front of the boiler.

45 Bridge wall construction

These tuyères are held together by the longitudinal bolts 38 that extend from the front of the retort to the rear.

50 Suitably formed tuyère blocks form the rear end of the furnace as at 39 having an arcuate face 40. The rear ends of these blocks rest upon their shoulders 41 on the ledge 42 of the angular transverse plate 43 which is mounted upon the shoulder 44 of the supporting wall 45. This 55 plate is provided with angular bridge wall brackets 46 which retain between the faces 47 and 48 the bridge wall blocks 49. An angular retaining plate 50 overlaps a shoulder 51 of such blocks 60 retaining them in position.

The bolts 38 enter the supporting wall 45. The bolts 45a join the plates 43 and 45. The bolts 46a join the plates 46 and 45.

65 Air re-circulation construction

Air from the air supply space 33 and 34 returns through the cut away passageways 36a into the space 37 into the apertures 52 cut through the feet 10 of the retort, and thence into the annular passageways 53 formed by annular flanges 61a on the lower fire box cover 61 and by annular sections 53a bolted into position by the bolts 53b on either side of the retort. This 70 annular passageway 53 is spaced from the fire box 3 for conveying the return air to points 75

above the annular filler for the delivery of air through the openings 54 into the top of the fire box around its inner margin, thus cooling the upper rivets 6 and driving the volatile gases, together with the air issuing through the ports 80 60, from adjacent the fire door. Filler blocks 57a rest on the bottom plate 57 and sections 53a.

The air issuing through the ports 60 is supplied from the air supply spaces 33 and 34 through the passageways 55. The lower part of these passageways is formed by the cover plate 56 mounted on the retort. The under side of this cover plate has an inwardly and upwardly extending tapered face for directing the coal into the space between the tuyères. On top of this cover plate rests the bottom 57 of an annular filler which has a flange 58 towards the furnace door and a plurality of spaced ribs 59 to form with plate 56 upwardly extending openings 60 for the escape of air. The upper part 90 of the passageways 55 is formed by the bottom plate 57.

The annular filler abuts against the plate 62 while the lower plate 61 with the angular ring plate 63 in cooperation with the retort forms 100 the remainder of the closure for the lower half of the fire box. The bolts 61b hold the ring plate 61 on the fire box 3.

The plate 62 receives the respective door halves 64 and 65 that are quadrant-shaped and which 105 are hinged along the line 66. They are supported on hinges comprising straps 67 and eyes 68 mounted on the hinge rod 69, the upper end of which is detachably mounted in the outwardly extending slotted lug 70. It is retained therein 110 by the cross pin 71. The lower end of the hinge pin 69 rests in a slot 72 of a cover plate 73. These doors are provided with internally disposed ribs 74 for strengthening purposes and to support the fire bricks.

The doors are held in latched closed position by the pivoted latch members 75 pivoted at 76 which have latching heads 77. These heads are provided with a cam face 78 which is adapted to be engaged by the cam nose 79 of the bell crank 120 lever 80 pivoted on the doors at 81. This lever is provided with a handle 82. Upon lifting the handle, the nose 79 depresses the latch 78 freeing it from the door and upon pulling the handle outwardly the door will swing outwardly on its 125 hinge bolt 69.

Pusher ram construction

The pusher ram consists of the head 83 which reciprocates in the outer end of the retort outside of the boiler. Its rear skirt rests upon the rear bottom plate 84 of the retort. Its top skirt is guided by the cover plate 85 upon which the slidably detachable hopper 86 is mounted. This 130 hopper is adapted to have its lower opening 87 above the ram 83. The precise construction of this slidable hopper is set forth and claimed in a co-pending application. It is operated by the handle 88 operating the hopper support 89 which slides between the shoulders 90.

The space beneath the reciprocating pusher 12 and 83 as at 91 can be cleaned of any accumulation of dust by the actuation of the trap door 92 which is pivoted at 93.

The ram 83 is connected by a pitman 94 to a crank 95 that is suitably actuated through a motor operating the gear within the gear box 97. This gearing and operating mechanism for the ram is the subject of said co-pending applica- 150

tion and is there described in detail and claimed.

Air delivery system

A fan 98 driven by the motor 96 which also 5 drives the ram delivers air into the following air duct system which in turn distributes it to the main air passageways 33 and 34 beneath the tuyères.

The fan 98 supplies air to the duct 99 which 10 is controlled by the damper or gate 100 through an exterior locking nut 101 thus proportioning the amount of air that will be delivered through the respective passageways 102 and 103 that communicate respectively to the air passageways 15 33 and 34.

It will be noted that by streamlining the fins forming the air ports in the tuyères that I am 20 enabled to secure greatly increased results from a given air pressure. By directing the air in the line of movement of the coal, there is no jamming of the air ports which are thus self-cleaned from the fuel.

It will be understood that I desire to comprehend within my invention such modifications as 25 may be necessary to adapt it to varying conditions and uses.

Having thus fully described my invention, what I claim as new and desire to secure by Letters Patent, is:

30 1. In combination, a boiler, a circular fire box therein, a retort on the bottom of said box, tuyères supported by said retort and the box walls, a common detachable means aligning said tuyères and connecting them to the fire box, and a bridge wall carried by said retort.

35 2. In combination, a boiler, a circular fire box therein, a retort on the bottom of said box, tuyères supported by said retort and the box walls, a common detachable means aligning said tuyères and connecting them to the fire box, and a bridge wall carried by said retort, said detachable means aligning the tuyères and also serving to align said bridge wall.

40 3. In combination, a boiler, a circular fire box therein, a retort on the bottom of said box, tuyères supported by said retort and the box walls, a supporting wall carried by said retort, a bridge wall bracket on the supporting wall, and bridge wall blocks supported by the bracket.

45 5. In combination, a boiler, a circular fire box therein, a retort on the bottom of said box, tuyères supported by said retort and the box walls, and a spacer plate on either side of said retort engaging said retort at one end and the outer ends of the tuyères at the other end, whereby an air chamber is formed beneath the tuyères on either side of the retort, means for forming an air chamber at the inner end of the retort between the bottom of the retort and the fire box, said air chamber having ports communicating with the chambers on either side of the retort, and means to space said retort from the bottom of the fire box for forming a return passageway for air from said air chamber to the front of the boiler.

50 6. In combination, a boiler, a circular fire box therein, a retort on the bottom of said box, tuyères supported by said retort and the box walls, and a spacer plate on either side of said retort engaging said retort at one end and the outer ends of the tuyères at the other end, whereby an air chamber is formed beneath the tuyères on either side of the retort, means for forming an air chamber at the inner end of the retort between the bottom of the retort and the fire box, said air chamber having ports communicating with the chambers on either side of the retort, means to space said retort from the bottom of the fire box for forming a return passageway for air from said air chamber to the front of the boiler.

55 said air chamber having ports communicating with the chambers on either side of the retort, means to space said retort from the bottom of the fire box for forming a return passageway for air from said air chamber to the front of the boiler, and ports in said means spacing the retort from the fire box at the front of the fire box whereby the air is delivered around the front end of the fire box between it and the sides of the retort.

60 7. In combination, a boiler, a circular fire box therein, a retort on the bottom of said box, tuyères supported by said retort and the box walls, and a spacer plate on either side of said retort engaging said retort at one end and the outer ends of the tuyères at the other end, whereby an air chamber is formed beneath the tuyères on either side of the retort, means for forming an air chamber at the inner end of the retort between the bottom of the retort and the fire box, said air chamber having ports communicating with the chambers on either side of the retort, means to space said retort from the bottom of the fire box for forming a return passageway for air from said air chamber to the front of the boiler, ports in said means spacing the retort from the fire box at the front of the fire box whereby the air is delivered around the front end of the fire box between it and the sides of the retort, and means of delivering said air at points above the retort adjacent the front of the boiler.

65 8. In combination, a boiler, a circular fire box therein, a retort on the bottom of said box, tuyères supported by said retort and the box walls, and a spacer plate on either side of said retort engaging said retort at one end and the outer ends of the tuyères at the other end, whereby an air chamber is formed beneath the tuyères on either side of the retort, means for forming an air chamber at the inner end of the retort between the bottom of the retort and the fire box, said air chamber having ports communicating with the chambers on either side of the retort, means to space said retort from the bottom of the fire box for forming a return passageway for air from said air chamber to the front of the boiler, ports in said means spacing the retort from the fire box at the front of the fire box whereby the air is delivered around the front end of the fire box between it and the sides of the retort, and means of delivering said air at points above the retort adjacent the front of the boiler, said means comprising a retort cover plate, an annular member spaced therefrom to form ports at the rear edges thereof between it and the cover plate.

70 9. In combination, a boiler, a circular fire box therein, a retort on the bottom of said box, tuyères supported by said retort and the box walls, and a spacer plate on either side of said retort engaging said retort at one end and the outer ends of the tuyères at the other end, whereby an air chamber is formed beneath the tuyères on either side of the retort, means for forming an air chamber at the inner end of the retort between the bottom of the retort and the fire box, said air chamber having ports communicating with the chambers on either side of the retort, means to space said retort from the bottom of the fire box for forming a return passageway for air from said air chamber to the front of the boiler, ports in said means spacing the retort from the fire box at the front of the fire box whereby the air is delivered around the front end of the fire box between it and the sides of the retort, means of delivering said air at points above the retort adjacent the front of the boiler.

- boiler, said means comprising a retort cover plate, an annular member spaced therefrom to form ports at the rear edges thereof between it and the cover plate, and means between said annular member and the top of the fire box for delivering air therebetween at that point. 80
9. In combination, a fire box, a retort therein, a pusher for supplying fuel through and over the sides of the retort, tuyères supported by the fire box and the retort forming air chambers on either side of the retort below the tuyères within the fire box, means of delivering air thereto, and means of returning air beneath the retort from the inner end to the fire door end of the fire box. 85
10. In combination, a fire box, a retort therein, a pusher for supplying fuel through and over the sides of the retort, tuyères supported by the fire box and the retort forming air chambers on either side of the retort below the tuyères within the fire box, means of delivering air thereto, means of returning air beneath the retort from the inner end to the fire door end of the fire box, and means of delivering said air at the front of the fire box from beneath the retort to a point above the retort. 90
11. In combination, a fire box, a retort therein, a pusher for supplying fuel through and over the sides of the retort, tuyères supported by the fire box and the retort forming air chambers on either side of the retort below the tuyères within the fire box, means of delivering air thereto, means of returning air beneath the retort from the inner end to the fire door end of the fire box, and means for delivering said air at the front of the fire box from beneath the retort to a point above the retort, said means for delivering said air comprising a delivery means just above the retort and a second delivery means at the front of the fire box just beneath the top thereof. 95
12. In combination in a boiler, a fire box, a retort supported thereby, tuyères supported by the fire box and the retort, an end wall supported on the inner end of said retort, means for supporting said tuyères in alignment on said end wall and retort. 100
13. In combination in a boiler, a fire box, a retort, an end plate on the inner end thereof, spacer plates mounted on either side of said retort on said end plate, tuyères bridging said spacer plates and retort walls to form air chambers on either side of the retort, the inner end of said retort having return air passageways communicating with a space between it and the fire box, and means to deliver air at the front of the retort from said space. 105
14. In combination in a boiler, a fire box, a retort, an end plate on the inner end thereof, spacer plates mounted on either side of said retort on said end plate, tuyères bridging said spacer plates and retort walls to form air chambers on either side of the retort, the inner end of said retort having return air passageways communicating with a space between it and the fire box, means to deliver air at the front of the retort from said space, a cover plate enclosing the top of the retort at the front thereof, an annular plate mounted thereon spaced from said plate and the upper interior portion of the fire box, there being ports between said cover plate and annular plate for the exit of said air passing around the retort, and ports between said annular plate and the top of the fire box for the exit of air passing around the plate between it and the fire box. 110
15. In combination in a boiler of a retort, a fire box for supporting the retort, tuyères supported therein, means of delivering air on the sides of the retort partially through the tuyères above the retort, means of returning a portion of said air from the inner end of the retort beneath it to a point at the front of the retort beneath it, and means of passing the air around the retort at the front and discharging it at the front above the retort into the fire box. 115
16. In combination in a boiler of a retort, a fire box for supporting the retort, tuyères supported therein, means of delivering air on the sides of the retort partially through the tuyères above the retort, means of returning a portion of said air from the inner end of the retort beneath it to a point at the front of the retort beneath it, means of passing the air around the retort at the front and discharging it at the front above the retort into the fire box, a portion of said means discharging air directly above the fuel in the retort and another portion at the top of the fire box directly beneath the front end thereof. 120
17. In combination in a boiler, a circular fire box mounted therein, a retort therein having the bottom thereof spaced from the fire box, tuyères mounted on the sides and inner end of said retort, an end plate on the retort, a bridge wall transversely arranged in association with the end plate and the inner end of the retort, spacers between the retort, tuyères and fire box to form air chambers for delivering the air through the tuyères and beneath the retort, means for returning said air from the rear of the retort beneath it to the front thereof, and means for distributing it in an annular path at the front of the retort. 125
18. In combination in a boiler, a circular fire box mounted therein, a retort therein having the bottom thereof spaced from the fire box, tuyères mounted on the sides and inner end of said retort, an end plate on the retort, a bridge wall transversely arranged in association with the end plate and the inner end of the retort, spacers between the retort, tuyères and fire box to form air chambers for delivering the air through the tuyères and beneath the retort, means for returning said air from the rear of the retort beneath it to the front thereof, means for distributing it in an annular path at the front of the retort, a part of it just above the retort and a part of it just beneath the top of the fire box. 130
19. In combination in a boiler, a fire box of circular form, a retort resting therein and spaced therefrom, tuyères having interlocking shoulders mounted on the margins of said retort, their outer ends resting on the inside of the fire box, arcuate spacer plates spaced from the fire box having flanges engaging depending shoulders on the tuyères and the lower sides of the retort, an end plate on the retort having shoulders for supporting said arcuate spacer plates. 135
20. In combination in a boiler, a fire box of circular form, a retort resting therein and spaced therefrom, tuyères having interlocking shoulders mounted on the margins of said retort, their outer ends resting on the inside of the fire box, arcuate spacer plates spaced from the fire box having flanges engaging depending shoulders on the tuyères and the lower sides of the retort, an end plate on the retort having shoulders for supporting said arcuate spacer plates, a detachable bracket for a bridge wall associated with said end plate, a bridge wall, a detachable retaining plate 140
- 145
- 150

- retaining the bridge wall and associated with the end plate.
21. In combination in a boiler, a fire box of circular form, a retort resting therein and spaced therefrom, tuyères having interlocking shoulders mounted on the margins of said retort, their outer ends resting on the inside of the fire box, arcuate spacer plates spaced from the fire box having flanges engaging depending shoulders on the tuyères and the lower sides of the retort, an end plate on the retort having shoulders for supporting said arcuate spacer plates, a detachable bracket for a bridge wall associated with said end plate, a bridge wall, a detachable retaining plate retaining the bridge wall and associated with the end plate, and an air chamber communicating with the space beneath the tuyères formed between the end of the retort and the end plate whereby air is delivered beneath the retort from the rear end thereof to the front thereof. 80 85
22. In combination in a boiler, a fire box of circular form, a retort resting therein and spaced therefrom, tuyères having interlocking shoulders mounted on the margins of said retort, their outer ends resting on the inside of the fire box, arcuate spacer plates spaced from the fire box having flanges engaging depending shoulders on the tuyères and the lower sides of the retort, an end plate on the retort having shoulders for supporting said arcuate spacer plates, a detachable bracket for a bridge wall associated with said end plate, a bridge wall, a detachable retaining plate retaining the bridge wall and associated with the end plate, and an air chamber communicating with the space beneath the tuyères formed between the end of the retort and the end plate whereby air is delivered beneath the retort from the rear end thereof to the front thereof, and means for distributing said air around the front of the retort and at points above the retort at the front thereof. 90 95 100
23. In combination in a boiler, a fire box, a retort therein forming with the fire box bottom an air passageway, tuyères mounted on said retort and extending to the walls of the fire box forming chambers on either side of the retort between it, the fire box wall and the tuyères, and means of delivering air to said chambers and from the chambers to the rear end of the air passageway. 105 110 115
24. In combination in a boiler, a fire box, a retort therein forming with the fire box bottom an air passageway, tuyères mounted on said retort and extending to the walls of the fire box forming chambers on either side of the retort between it, the fire box wall and the tuyères, means of delivering air to said chambers and from the chambers to the rear end of the air passageway, and means of balancing and proportioning the air delivered to the respective chambers on either side of the retort. 120 125
25. In combination in a boiler, a fire box, a retort therein, tuyères mounted on said retort and extending to the walls of the fire box forming chambers on either side of the retort between it, the fire box and the tuyères, means of delivering air to said chambers, and means of balancing and proportioning the air delivered to the respective chambers on either side of the retort, and means of returning the air not delivered through the tuyères from the inner end of the retort beneath it to a point at the front of the fire box. 130 135 140 145 150
26. In combination in a boiler, a fire box, a re-
- tort therein, tuyères mounted on said retort and extending to the walls of the fire box forming chambers on either side of the retort between it, the fire box and the tuyères, means of delivering air to said chambers, and means of balancing and proportioning the air delivered to the respective chambers on either side of the retort, and means of returning the air not delivered through the tuyères from the inner end of the retort beneath it to a point at the front of the fire box, and means of distributing said air in an annular path adjacent the interior of the fire box and discharging it inwardly adjacent the front thereof. 155
27. In combination in a boiler, a circular fire box therein, a retort mounted upon the bottom of the fire box having its bottom spaced from the fire box, a reciprocating pusher carried in said retort forming a portion of the bottom thereof, a tapered end wall in the retort, a spaced end plate, tuyères mounted on the upper edges of said retort having air openings discharging thereover, and inner depressed upper surfaces for forming refuse pits, a bridge wall associated with said end plate extending across said tuyères and refuse pits. 160
28. In combination in a boiler, a circular fire box therein, a retort mounted upon the bottom of the fire box having its bottom spaced from the fire box, a reciprocating pusher carried in said retort forming a portion of the bottom thereof, a tapered end wall in the retort, a spaced end plate, tuyères mounted on the upper edges of said retort having air openings discharging thereover, and inner depressed upper surfaces for forming refuse pits, a bridge wall associated with said end plate extending across said tuyères and refuse pits, and a common aligning means carried by said boiler extending through said fire box and said tuyères to said end plate for supporting and aligning said tuyères. 165
29. In combination, a circular fire box, a retort resting on the bottom thereof and forming with the bottom an air passageway, tuyères extending from the top of the retort to opposite sides of the fire box, and forming with the fire box air chambers connected to the rear end of the air passageway, said several parts occupying approximately one-half of the circular space in the fire box. 170
30. In combination, a circular fire box, a retort resting on the bottom thereof, tuyères extending from the top of the retort to opposite sides of the fire box, said several parts occupying approximately one-half of the circular space in the fire box, a bridge plate at the fire door end of the retort resting upon it and extending across it, and annular sections spaced from said bridge plate and the upper half of said fire box providing an annular passageway between it and the fire box, and reciprocating means in said retort forming the bottom thereof for delivering fuel therethrough and therefrom. 175
31. In a stoker, a boiler, a fire box disposed therein, a retort in the fire box, air delivery passageways on either side of the retort to the end thereof, said retort forming with the fire box a return passageway to the front of the fire box communicating with the passageways, a cover plate for said retort, filler plates associated therewith, spaced annular plates arranged above the retort within the fire box having outlet openings adjacent their interior margins along the interior of the fire box, and means for permitting the communication of the return air there- 180 185 190

with through the walls of the retort from a point beneath the retort whereby the return air is delivered over the retort and within the upper half of the fire box adjacent the wall thereof.

32. In a stoker, a boiler, a fire box disposed therein, a retort in the fire box, air delivery passageways on either side of the retort to the end thereof, said retort forming with the fire box a return passageway to the front of the fire box communicating with the passageways, a cover plate for said retort, filler plates associated therewith, spaced annular plates arranged above the retort within the fire box having outlet openings adjacent their interior margins along the interior of the fire box, and means for permitting the communication of the return air therewith through the walls of the retort from a point beneath the retort whereby the return air is delivered over the retort and within the upper half of the fire box adjacent the wall thereof, and rivets for joining said fire box and boiler, the interior of which are cooled by said returning air.

33. In combination, a circular fire box, a retort resting therein, air passageways on either side thereof, the tops of which passageways are formed at one end by filler blocks, a spaced cover plate resting on said retort and spaced from said

filler blocks to permit air to circulate beneath the filler blocks from the air passageways, means at the inner end of said retort for returning air therebeneath to the forward end thereof, means at the bottom of said forward end of the retort for discharging air into annular passageways beneath said first mentioned passageways and extending upwardly and completely around the interior of the fire box, said annular passageway having discharge ports adjacent the fire box above the filler blocks.

34. In combination, a fire box, a retort therein, lateral air passageways, tuyères supported between the fire box and the retort for laterally discharging air over the retort, a cover for the outer end of the retort, a filler block spaced therefrom to discharge air inwardly over the front of the retort, means of delivering air from the ends of the lateral air passageways to the bottom of the retort and between the bottom of the retort and the fire box to the front of the retort, and an annular passageway communicating with the front and bottom of the retort for the delivery of said return air within the annular front margin of the fire box, and means of discharging said air within the fire box in an annular stream above the filler block.
